UNITED STATES PATENT OFFICE.

EDWARD L. DUNN, OF WORCESTER, MASSACHUSETTS.

INTERLOCKING AND DOOR-OPERATING DEVICE FOR ELEVATORS.

1,232,903.

Specification of Letters Patent. Patented July 10, 1917.

Application filed September 11, 1914. Serial No. 861,289.

To all whom it may concern:

Be it known that I, EDWARD L. DUNN, a citizen of the United States, residing at Worcester, in the county of Worcester and 5 State of Massachusetts, have invented a new and useful Interlocking and Door-Operating Device for Elevators, of which the following is a specification.

The main purpose of this invention, in 10 the case of elevators, is to provide means for controlling the car door as well as the landing door, and prevent movement of the car while any door is open, likewise to prevent movement of any of the doors while 15 the car is in motion.

This invention is a distinct improvement 20 in this art because it compels the closing of the elevator car door as well as the landing door before the car can be started. Also the same device with two handles controls 25 the operation of all doors as well as operating the car, and it is not, therefore, necessary for the doors to be moved by hand in the usual manner or by power in the usual manner.

I provide a device located within the car, having two crank handles arranged in such 30 a manner that when one handle is moved, the other is securely locked against movement. One handle manipulates a switch, which is capable of giving all necessary motions to the car; the other handle manipulates the doors. I have shown two ways in which the doors can be manipulated, one 35 being hand operation, that is, the doors are connected to a crank by suitable gearing and when the crank is turned, the doors move correspondingly. The other way in which the doors are moved is by power; that is, 40 the doors are moved by a motor, and the crank, instead of being mechanically connected to the doors, manipulates a switch which governs the motor. The motor, however, is provided with an automatic stopping 45 provision as the door completes its opening or closing movement.

Further features of the invention are:—

Improved electric interlocks operated by 50 the car operating switch and door switches; Improved door connections both mechanical and magnetic;

Improved variable speed means for cushioning the opening and closing movements of the doors;

Improved self-closing and locking means 55 for the doors.

Reference is to be had to the accompanying drawings, in which—

Figure 1 is a front elevation showing the form of the invention in which the door is 60 hand-operated and showing the interior of the controller;

Fig. 2 is a side elevation of the door operating mechanism thereof with the controller and a part of the door operating means in 65 central vertical section transverse to Fig. 1;

Fig. 3 is a front elevation of the interlocking mechanism on enlarged scale;

Fig. 4 is a sectional view on the line 4—4 of Fig. 3;

Fig. 5 is a front elevation of part of the controlling device;

Fig. 6 is a horizontal section of the car and well showing the car door and landing door and the connections between them;

Fig. 7 is an elevation of the same showing the parts in two positions;

Fig. 8 is an elevation of the car door showing the connections for operating it in two positions corresponding to Fig. 7;

Fig. 9 is a plan on enlarged scale showing the mechanical connection between the car and landing doors;

Fig. 10 is a front elevation of the same on enlarged scale;

Fig. 11 is a similar view showing the parts modified to provide a magnetic connection instead of a mechanical one;

Fig. 12 is a plan of the parts shown in Fig. 11 with the magnet in section;

Fig. 13 is a side elevation with parts in central vertical section of a controlling device similar to that shown in Fig. 2 but arranged for the operation of the door by power;

Fig. 14 is a rear view of the same showing the controller in rear elevation;

Fig. 15 is a side elevation of one of the switches appearing in Fig. 14;

Fig. 16 is an elevation similar to Fig. 14 showing one interlocking device on enlarged scale;

Fig. 18 is a central longitudinal sectional view of a portion of the motor and brake and their connections;

Fig. 19 is a diagrammatic view showing

the wiring for the construction shown in Figs. 13 to 18 inclusive;

Fig. 20 is a front elevation of a controlling device and door connections for use in 5 a hydraulic elevator; and

Fig. 21 is a side elevation of the same.

Referring first to Fig. 1 a complete car switch is shown having all necessary contacts for controlling an elevator motor by 10 means of a magnetic controller. These contacts I have labeled A¹, A², A³, A⁴, A⁵, and A⁶, A⁷, A⁸, A⁹, A¹⁰. They operate in the usual manner, that is, when the insulated contactor C is moved to engage one set of 15 contact fingers, the elevator starts and moves in one direction, and when the contactor C is moved in the reverse direction from center to engage the contact fingers the elevator starts and moves in the reverse direction. 20 It will be noted that the contactor C is directly connected to the operating crank handle A through a shaft a' and is provided with a self-centering spring D, which will return the lever A and contactor C to central position when reversed, causing it to 25 lock at the notch E.

A slotted flange F is arranged on the shaft a' to pass through a similar slotted flange G, on a shaft I at right angles to the shaft 30 a'. These flanges thus being at right angles to each other, it can be readily seen that if the position of either of these flanges is moved, even a slight part of a revolution, the other flange is locked against movement. 35 The door handle B is connected through bevel gearing J to the door operating shaft H. One of the bevel gears J is directly connected to the shaft I and flange G. Therefore, when the handle B is turned, the shaft 40 H is revolved, and the car switch is locked by means of the flange G.

The shaft H passes through the car floor and is connected with bevel gears K and L. On the same shaft with the gear L is an 45 eccentric gear M, this engaging with a rack N. It will be noted that the rack is part of a yoke N' which goes around the gear M, for the purpose of keeping the teeth always in mesh. When the shaft H is revolved, a 50 differential movement is imparted to the rack N. In other words, the rack starts slowly at the beginning of stroke and stops slowly at the end of stroke. As this yoke is connected to the swinging arm O, which 55 is attached to the door, the door is started slowly and stopped slowly, on account of the mechanical cushioning effect of the eccentric gear M. It is well to note here that while one car door only is shown, multiple 60 doors, that is two or more doors, could be very conveniently arranged to work as well as one.

Referring to Figs. 7 and 8, door connections of the "Russwin" form are shown in 65 detail, the swinging arm O being pivoted

near the car floor and connected to the front part of the car door by a lever P. At the end of this lever, a projecting lug R is provided, this passing through a slot S, which forms part of the landing door connections. 70

The landing door is provided with toggle connections T and U which are set at dead center when the door is closed, therefore, the door is locked against movement from the outside. An additional lever V is provided 75 with a slotted end S, also a slotted connection to the cross lever T. The lever U, at the rear end, is connected to a spring actuated dash pot W. The door movement takes place as follows:

When the car stops approximately level with the landing, projection R on the car door passes into the slot S which is part of the landing door lever V. When the car door is moved slightly, the lug R engaging 80 one side of the slot S, swings the lever V to the right, with the result that the toggle levers T and U rise upward, overcoming the spring in the dash pot W. It can be noted at this stage, that with the movement of the 85 door, the car operating switch is securely locked. When the car door is returned to a closed position, the landing door continues to move slightly, on account of the spring in the dash pot W, thus leaving the projecting 90 lug R in the center of the slot S and not against one side. Therefore, as the car passes up and down the hatch, there is no scraping contact at the landing door slots. Although I have shown the Russwin door 95 controller, it will be understood that my invention can be used with many other forms of door controller and that the latter is not my invention. It should be noted that in addition to the mechanical cushioning effect caused 100 by the eccentric gear M, the dash pot W also exerts a cushioning influence on the final movement of the landing door, thus a double cushion is provided.

Another feature to take note of is the door 110 switch. When the landing door opens, the door switch button X being spring compressed, opens with the door, separating the contacts X¹ and X². A similar door switch could be provided for the car door. Instead 115 of the slot and pin described in the foregoing, a magnetic connection between the car door and landing door can be used as shown in Figs. 11 and 12. In this case the car door is provided with a magnet Y. This magnet 120 has a flanged face which engages a flanged plate or armature Y², the magnet being connected by means of a flexible electric cable Y³ or other suitable electrical connection. The door magnet can receive this circuit only 125 while the car operating switch is at off position. This circuit passes through contacts B¹—C—B². It will be noted that with the car switch only in central or off position, the door magnet circuit is closed by these con- 130

tacts. Therefore, when the car stops approximately level, the magnet Y attracts the armature Y^2 , there being sufficient lost motion provided to allow the armature to swing into engagement with the magnet. The result is that as the car door is moved, the landing door is moved in a similar manner, being magnetically connected to the car door. This magnetic connection remains until the car switch is moved to start the car. If the landing door is not fully closed, the spring dash pot W will completely close the door. A feature worthy of note is that the car must stop approximately level, in order to operate the landing door. In the mechanical connections the slot regulates this; in the magnetic connections, the dimensions of the armature regulate the point at which the door can be moved.

In the foregoing I have shown how the doors are opened and closed manually by means of the crank B. I have further shown how with the movement of this crank, the car is securely locked mechanically and electrically, against movement. I have previously pointed out also that only with the handle B in an upright central position, can the car switch operating handle A be moved, and when handle A is moved handle B is instantly locked against movement. Therefore, the handle A which operates the car can be moved only when handle B is in central position with the door closed; likewise the door operating handle B can be moved only when the handle A is in off or central position.

Referring now to Figs. 13 to 17, I will describe how the door can be operated by a power motor, instead of by hand. The locking connections F and G are the same as the hand operated arrangement, the main difference being that the shaft connecting the bevel gear L and eccentric gear M is extended to the left and is directly connected to a worm gear Z which is in turn connected to the motor shaft through a worm Z^1 . The switch lever handle A is shown with the handle reversed, and instead of the handle B, I have shown a switch lever handle B^3 , this being provided with metallic contactors B^4 , B^5 , and arranged to engage contacts B^6 , B^7 , B^8 , B^9 , or B^{10} , B^{11} , B^{12} and B^{13} . Therefore, if the handle B^3 is moved to the right or left, suitable connections are made to the power motor. It will be noted that when the motor is in motion, in addition to moving the door by means of eccentric gear M, the shaft H is revolved the same as in hand operation, thus serving two purposes: first, to lock the car operating handle A against movement while the door is open even if the door controlling handle B^3 has been moved back to neutral position; and second, to automatically open the switch B^{14} or B^{15} as the case may be. The opening of this switch

automatically stops movement of the motor as the door reaches open or closed position. These switches are caused to open by cams C^1 or C^2 . The two cams C^1 and C^2 , being attached at different angles, to the same shaft as the bevel gear J, necessarily move with the gear and with the shaft H. When the door is either closed or fully open one cam allows its switch to close. At the end of the next opening or closing motion the switch that has been closed is opened and the other closes, so that the door can be moved back. The time of opening each switch is necessarily regulated by the position of the cam on the shaft, set screws being provided for this purpose. The shaft turning less than one full revolution, it is simply a matter of setting each cam in the right position to open the switch at the right time.

Interlocking connections between the car operating handle A and the door operating handle B^3 are arranged, so that only one of the two mentioned handles can be moved. This interlock is clearly shown in Fig. 16, where a double-slotted flange F^1 is provided on the shaft a^2 in addition to the other slotted flange F. Moving with the door controller handle B^3 are a pair of arms G' adapted to interlock with the flange F^1 . This interlock directly prevents the operation of either handle A or B^3 except when the other is in neutral position.

Fig. 19 shows all circuits complete for a compound wound direct current motor. A motor of this type is shown for the purpose of description, although I do not limit myself to this type of motor, or, in fact, any other, as there are many ways in which good results could be obtained by other types of motors. Fig. 18 shows a magnetic brake Z^3 , this being in series circuit with the series field of the motor, arranged to act automatically with the starting and stopping of the motor. Thus when the series circuit current passes through the brake magnet, the armature Z^4 is attached to the magnet, overcoming the springs Z^5 , releasing the friction between the disks Z^4 , Z^5 . When the motor circuit is interrupted, the springs Z^5 throw the armature plate Z^4 into frictional engagement with revolving plate Z^5 , causing the motor to stop quickly. Where a motor is frequently started, it is desirable to keep the shunt field energized. In diagram, Fig. 19, I have, therefore, shown a shunt field in continuous circuit from the line switch, I will now describe these circuits fully.

Starting at the plus side of line through wire 1 a circuit can be traced through the shunt field to the opposite side of the line through a wire 2. The circuit from wire 1 branches through the series field and series brake to a contact B^6 . When the switch lever B^3 is moved to the right, the two con-

tacts B^6 and B^7 are bridged by B^4 , and contacts B^8 and B^9 are bridged by B^5 . Therefore, the circuit from series field passes through contacts B^6 and B^7 , through automatic switch B^{14} , through armature to contacts B^8 , B^9 to minus side of line.

It should be noted that the automatic switch B^{15} is open, showing that when the doors are closed, this switch automatically 10 opens, and the motor circuit can be closed to operate only in the opening direction. As the motor starts, the automatic switch B^{15} closes with the result that the motor can be started, stopped or reversed at will, except 15 when the door is at the end of its movement in one direction or the other. With the door open, automatic contact B^{15} would be closed, while B^{14} would be open, and to close the door, it would be necessary to reverse the 20 motor by moving the switch B^3 in the reverse direction, the circuits being the same as above described, except they would take place through contacts B^{10} , B^{11} , B^{12} and B^{13} , which would reverse the armature current. 25 As the door motor circuits have now been described, I will point out that the feed to the car switch which supplies current for operating the elevator controller passes through the door switches; these I have labeled D^1 , D^2 , D^3 , D^4 , and D^5 , the last one being attached to the car door. This line 30 continues to the principal contacts A^1 A^6 in the car switch, and the result is that if any of the landing doors, or the car door is 35 open, the car cannot be moved for lack of starting energy, and is, therefore, electrically prevented from starting as well as mechanically interlocked.

I will not describe further the elevator 40 controller circuits, as they form no part of this invention. I have shown that the feed passes through the door switches and I have also shown a sufficient number of contacts in Fig. 1, which were labeled A^1 , A^2 , A^3 , A^4 , A^5 , 45 and A^6 , A^7 , A^8 , A^9 and A^{10} , these all being mounted upon a base of insulation and are for the purpose of connection to the elevator controller.

The door magnet circuit can be traced 50 from the plus side of the line through car switch contacts B^1 , B^2 , through the door magnet to the minus side of the line; obviously the door magnet is energized only when the car switch is in off or central position.

It will be understood that only a part of this diagram applies to the form of the invention shown on the first sheet of drawings.

In the foregoing I have described conditions in connection with electrically operated elevators, that is to say, I have shown and described car switches, etc., capable of use in connection with electrically operated elevators.

In Figs. 20 and 21, I have shown apparatus capable of use in connection with a hydraulic elevator in accordance with this invention. While the construction is different, the principle is exactly the same, two levers being shown, one, the central lever 20, 65 being equivalent to the controller lever A, the elevator moving in response to this lever. The other lever 21, shown at the end of the quadrant, is likewise equivalent to the lever B, as it is connected to the door swinging 70 arm O by means of the link 22.

The interlocking devices are practically the same as previously described, the sector 23 being attached to the lever 20, moves with it. Therefore, when the lever 20 is 80 moved the slot shown in 23 is moved, thus preventing movement of the swinging arm O, on account of the lug 24 which is pivoted the same as the swinging arm O, and consequently moves with it and must have a free 85 passage through the slot as the swinging arm moves to and fro. On the other hand, when the swinging arm O is moved and the door is opened, the lug 24 enters the slot in the sector 23, thus locking the lever 20 90 against movement.

I will not show electrical circuits for operating the power door, in connection with Figs. 20 and 21, as it is clearly obvious to those skilled in the art, that the arrangement 95 would be similar to that which I have outlined previously.

Although I have shown and described the invention as applied only to certain kinds of elevators, I am aware of the fact that my 100 invention could be applied to other devices and other kinds of elevators, and many changes can be made in the mechanical and electrical connections, without departing 105 from the scope of the invention as expressed in the claims, therefore I do not wish to be limited in these respects, but what I do claim is:—

1. The combination with a car having a 110 door, a motor controller thereon, a door controller on said car, said door controller having means for controlling the operation of the car door, means whereby neither one of said controllers can be operated unless the other is in neutral or off position, a door 115 magnet, and means on said motor controller for connecting said door magnet with a source of power only when the motor controller is in neutral position.

2. The combination with a car having a 120 door, of a handle in the car, connections from the handle for operating the car door, a second handle in the car, connections from the second handle for controlling the operation of the car, two shafts, one connected 125 with each of said handles to be turned thereby, and means on each of said handles for interlocking with said means on the

other shaft for preventing each shaft from turning at any time except when the other shaft is in neutral or inoperative position.

3. The combination with a car having a door, of two handles in the car in alinement with each other when in neutral position, connections from one handle for operating the door, connections from the other handle for controlling the operation of the car and 10 two flat disks at right angles to each other, one connected to be turned on its axis by one handle, and the other by the other, each disk having a slot in its flat edge for the edge of the other, said disks being so set that 15 said slots register when one handle is in position to close the door, and the other in position to stop the operation of the car.

4. The combination with a car and a door therefor, of a box, two handles pivoted 20 thereon, means connected with one handle for operating the car door, means connected with the other handle for controlling the operation of the car, a shaft connected to be operated from one of said handles and 25 having a disk thereon provided with a notch, a second shaft connected to be operated from the other handle and having a notched disk thereon adapted to enter said notch and to engage a face of said disk when the disk 30 is turned to non-registering position, said handles being connected with the disks in such a way that they are in neutral position when the notches register, the second shaft being connected with the door.

5. The combination with a car and a door therefor, of a box, two handles pivoted thereon, means connected with one handle for controlling the operation of the car, a shaft connected to be operated from one of 40 said handles and having a disk thereon provided with a notch, and a second shaft connected to be operated from the other handle and having means thereon adapted to enter said notch and to engage a face of 45 said disk when the disk is turned to non-registering position, said handles being connected with the disk and means in such a way that they are in neutral position when the means and notch register.

6. The combination with a car and a door therefor, of a vertical shaft extending down through the floor of the car, means connected with said shaft for operating the door and for slowing up the same at each 55 end of the travel thereof, means in the car for controlling the operation of the car, and means positively connected with said shaft for preventing the operation of said means to start the car when the door is open.

7. The combination with a car and a controller box therein, of a handle on the box for controlling the operation of the car, yielding means for holding said handle in neutral inoperative position, a shaft, means

connected with and operated by said shaft 65 for operating the door, a handle on the controller box having connections for controlling the operation of said shaft, and means whereby when one of said handles is in operative position it prevents the other handle 70 from being moved away from neutral inoperative position.

8. The combination with a car and a door therefor, of a shaft extending down through the floor of the car, means connected with said shaft for operating the door, means in the car for controlling the operation of the car, and means positively connected with said shaft for preventing the operation of said means to start the car when the door is open. 80

9. The combination with a car and a door therefor, of a shaft extending down through the floor of the car, means connected with said shaft for operating the door, a crank in the car for controlling the operation of the car, means connected with said shaft for preventing the operation of the crank to start the car when the door is open, and means connected with the crank for positively preventing the operation of said shaft 90 to open the door when the car is in motion.

10. The combination with a car and a door therefor, of a shaft extending down through the floor of the car, an eccentric gear connected with said shaft to turn therewith, a rack meshing with the gear, means connected with the rack and with the door for operating the door, means for operating said shaft and gear, a crank for controlling the motion of the car, and means positively operated by said shaft for locking said crank when the shaft is in such position as to open the door. 95

11. The combination with a car and a door therefor, of a shaft extending down through the floor of the car, an eccentric gear connected with said shaft to turn therewith, a rack meshing with the gear, means connected with the rack and with the door for operating the door and slowing up its motion at each end of its stroke, and means for operating said shaft and gear. 100

12. The combination with a car and a door therefor, of an eccentric gear, a rack meshing with the gear, means connected with the rack and with the door for operating the door and slowing up its motion at each end of its stroke, and means for operating said gear. 115

13. The combination with a car and a door therefor, of a shaft extending down through the bottom of the car, a transverse shaft under the car connected with said shaft, an eccentric circular gear mounted on the transverse shaft, and a rack meshing with said 125 gear and connected with the car door for operating it.

14. The combination with a car and a

door therefor, of a shaft extending down through the bottom of the car, a transverse shaft under the car connected with said shaft, an eccentric circular gear fixed on the transverse shaft, and a rack meshing with said gear and connected with the car door for operating it, said rack being provided with a yoke, the rack teeth being on the inside of one leg of the yoke, whereby the remainder of the yoke serves to guide the yoke with respect to the eccentric gear and keep the teeth in mesh.

15. The combination with a car and a door therefor, of a controller box, a crank handle on the controller box, means connected with the handle for controlling the operation of the door, said means comprising a shaft under the car, an eccentric circular gear fixed on the shaft, and a rack meshing with said gear and connected with the car door for operating it, said rack being provided with a yoke, the rack teeth being on the inside of one leg of the yoke, whereby the remainder of the yoke serves to guide the yoke with respect to the eccentric gear and keep the teeth in mesh.

16. The combination with a car and a door therefor, of a controller box, a crank handle on the controller box, means connected with the handle for controlling the operation of the door, said means comprising a shaft extending down through the bottom of the car, a transverse shaft under the car connected with said shaft, an eccentric circular gear mounted on the transverse shaft, and a rack meshing with said gear and connected with the car door for operating it.

17. The combination with a car and a door therefor, of a controller box, a crank handle on the controller box, means connected with said crank handle for controlling the operation of the car, a second handle on the controller box, means connected with the second handle for controlling the operation of the door, said means comprising a shaft extending down through the bottom of the car, a transverse shaft under the car connected with said shaft, an eccentric circu-

lar gear fixed on the transverse shaft, and a rack meshing with said gear and connected with the car door for operating it, said rack being provided with a yoke, the rack teeth being on the inside of one leg of the yoke, whereby the remainder of the yoke serves to guide the yoke with respect to the eccentric gear and keep the teeth in mesh, and means for preventing each handle from being moved except when the other is in neutral position.

18. The combination with a car having a door thereon, of a landing door, an electromagnet located on one of said doors, and a metallic member on the other, said magnet and member being in registration with each other when the doors are in registration, and means for energizing said magnet.

19. The combination with a car having a controller thereon for controlling the operation of the car, a car door, a landing door, an electromagnet located on one of said doors, a metallic projection located on the other in registration with the magnet when the two doors are in registration, and means operated by said controller for energizing said magnet when the controller is in neutral position.

20. The combination with a car having a door, a motor controller thereon, a door magnet having means for connecting the car door with a landing door and causing them to move together, said motor controller having means for connecting the door magnet with a source of power only when the motor controller is in neutral condition.

21. An elevator comprising in combination, a car having a door, a floor level door, and electric means for connecting said doors with each other when the car arrives at a floor level.

In testimony whereof I have hereunto set my hand, in the presence of two subscribing witnesses.

EDWARD L. DUNN.
